UNITED STATES PATENT OFFICE.

JOHN DOUGLAS, OF ELIZABETH, NEW JERSEY, ASSIGNOR TO THE SINGER MANUFACTURING COMPANY, A CORPORATION OF NEW JERSEY.

SEWING-MACHINE HEMMER.

SPECIFICATION forming part of Letters Patent No. 732,399, dated June 30, 1903.

Application filed June 30, 1902. Serial No. 113,821. (No model.)

To all whom it may concern:

Be it known that I, JOHN DOUGLAS, a citizen of the United States, residing at Elizabeth, in the county of Union and State of New Jersey, 5 have invented certain new and useful Improvements in Sewing-Machine Hemmers, of which the following is a specification, reference being had therein to the accompanying drawings.

10 This invention relates to that class of sewing-machine hemmers—such, for example, as that shown and described in United States Patent No. 623,891—which is adjustable, so that hems of different widths may be formed 15 by the use thereof; and the invention has for its object to provide an efficient hemmer of the class referred to, which is so mounted on the machine-head as to be readily thrown up out of the way when not in use without being 20 detached from the machine, as also to provide means for adjustably supporting the hemmer in different positions relative to the work-plate and the needle of the machine.

In the accompanying drawings, Figure 1 is 25 a front end view of one form of Singer hem-stitch-sewing machine with the invention applied thereto, but with the parts below the work-plate omitted. Fig. 2 is a plan view of the hemmer and its supporting-bracket. Fig. 30 3 is a bottom view of the hemmer. Fig. 4 is a front view of the hemmer, partly in section on line 4 4, Fig. 2. Fig. 5 is a view of the hemmer and its supporting-bracket from the side opposite that shown in Fig. 1.

35 Referring to the drawings, 12 denotes the work-plate of the machine, and 13 the head at the forward end of the usual bracket-arm. Attached to the head 13 is a bracket 15, to which is secured a sector-plate 16. Pivoted 40 mounted on the bracket 15 by a screw 17 is a supporting-arm 18, to which is attached a frame 19, which supports the left-hand and non-adjustable edge-turner or folder 20, a tongue 21, extending within the upper and 45 lower parts of said folder 20, and an edge-guide 22. The said frame 19 has a shank or standard 23, provided with a slot 24, through which passes a set-screw 25, which secures said frame to the said supporting-arm 18 in 50 such manner as to permit the hemmer to have a limited vertical adjustment relative to the

work-plate of the machine to accommodate different kinds or thicknesses of work.

Supported by the frame 19 is a second frame 26, having a slot 27, fitting a guiding-rib 28 on the frame 19, the said frame 26 carrying the right-hand or adjustable edge-turner or folder 29, within which is arranged a tongue 30, extending forward from a guide-plate 31, over which the goods to form the hem are 60 folded, said guide-plate having a lateral extension 33 with a turned-up lip 34 attached to the frame 26 and which frame 26 carries the right-hand folder 29 and the plate 32, extending to the left of said folder, and which plate 65 32 supports the lower ply of material forming the hem.

The slot 27 in the frame 26, and in which the guiding-rib 28 fits, permits of a lateral adjustment to the right or left of the right-hand folder 29 relative to the stationary or non-adjustable left-hand folder 20 for the purpose of adapting the hemmer to the formation of hems of different widths, the said frame 26 and the parts carried thereby being secured 70 in any desired position of adjustment by the set-screw 35.

Overlying the adjustable right-hand folder 29 is a smoothing-plate 36, which assists in holding the fabric forming the hem smooth 80 and taut, more particularly when wide hems are being formed.

The sector-plate 16 is provided at its lower side with a horizontal lip 37, in which is tapped an adjustable stop-screw 38, against which 85 the horizontal part of the arm 18 abuts and which screw serves as an adjustable stop for said arm, so that the forward end of the left-hand hemmer may be held in different positions of adjustment relative to the needle of 90 the machine by varying the position of the said stop-screw, said screw being held in any desired position of adjustment by a winged set-nut 39.

Owing to the manner in which the hemmer 95 is supported on the head 13 by the pivoted arm 18 it will be obvious that the said hemmer may be turned up out of the way, as denoted by dotted lines in Fig. 1, when not desired for use, and to retain the hemmer in 100 either an operative or inoperative position a suitable friction device for said arm is pref-

erably provided. Such friction device consists in the present instance of a plate 40, attached to the said arm 18 and one part of which bears against the sector-plate 16 with sufficient force or friction to retain the arm 18 in any position against accidental displacement to which it may be adjusted, said plate 40 being preferably of spring metal, so as to have some resiliency, but still being sufficiently stiff so that in coöperation with the said sector-plate said plate 40 will serve to steady the pivoted arm 18 and the hemmer supported thereby laterally.

The bearing-point of the friction-plate 40 against the sector-plate 16 is at some distance from the pivot of the arm 18, so that said friction and steadyng plate will have considerable leverage on said arm in steadyng the latter.

20 It will be noted that the arm 18 directly supports the frame 19 and that said frame 19 supports the frame 26. Thus the arm 18 supports, either directly or indirectly, all of the parts of the double hemmer, and as the screw 25 17, on which the arm 18 is pivoted, is at right angles to the direction of the feed of the work in sewing the double hemmer is pivotally mounted, so that all of its parts may be swung up out of the way in front (toward the 30 operative) of the head or arm of the machine when not desired for use, leaving the work-plate of the machine entirely unobstructed.

Having thus described my invention, I claim and desire to secure by Letters Patent—

35 1. In a sewing-machine, the combination with the head thereof, of an arm pivotally attached to said head by a pivot disposed at right angles to the direction of the feed of the 40 work, a double hemmer all the parts of which are supported by said arm, and a steadyng friction device, at a distance from the pivot of said arm, for retaining the said pivotally-mounted hemmer either in an operative or in 45 an inoperative position, and for steadyng said arm.

2. In a sewing-machine, the combination with the head thereof, of an arm pivotally attached to said head, by a pivot disposed at 50 right angles to the line of the feed of the work, so that the said hemmer may be turned up in front of the said head, a double hemmer all the parts of which are supported by said arm, a device for retaining the said pivotally-

55 mounted hemmer either in an operative or an inoperative position, and for steadyng said arm, and an adjustable stop by which the operative forward position of the said pivotally-mounted hemmer, relative to the needle of the machine, may be varied.

60 3. In a sewing-machine, the combination with the head thereof, of a sector-plate rigidly attached to said head, an arm pivotally mounted on said head adjacent or contiguous to said sector-plate and provided, at a distance from its pivot, with a friction and steadyng plate bearing against said sector-plate, and a hemmer supported by said pivotally-mounted arm.

4. In a sewing-machine, the combination 70 with the head thereof, of a sector-plate rigidly attached to said head, an arm pivotally mounted on said head adjacent or contiguous to said sector-plate and provided, at a distance from its pivot, with a friction and steadyng plate bearing against said sector-plate, and a hemmer supported by said pivotally-mounted arm, said sector-plate being provided with an adjustable stop to vary the working position of the hemmer relative to 75 the needle of the machine.

5. An adjustable sewing-machine hemmer adapted for pivotal attachment to the head of the machine and comprising the supporting-arm 18, a frame 19 rigidly attached to said arm and carrying a stationary or non-adjustable left-hand folder, a frame 26 laterally adjustable on said frame 19 and carrying a right-hand folder.

6. An adjustable sewing-machine hemmer 90 adapted for pivotal attachment to the head of the machine and comprising the supporting-arm 18, a frame 19 rigidly attached to said arm and carrying a stationary or non-adjustable left-hand folder, an intervening tongue 95 and an edge-guide; a frame 26 laterally adjustable on said frame 19 and carrying a right-hand folder, an intervening tongue, a guide-plate 31 and a supporting-plate 32, and which plates 31 and 32 are laterally adjustable with 100 said right-hand folder.

In testimony whereof I affix my signature in presence of two witnesses.

JOHN DOUGLAS.
